ELECTRICAL CIRCUIT BREAKER

Oakley K. Beckler, Dallas, Tex., assignor of twenty-two and one-half per cent to Marion H. Rowe, Dallas, Tex., and seventy-two and one-half per cent to Joseph H. Reynolds, Cisco, Tex., and five per cent to Jack A. Schley, Dallas, Tex.

Application September 2, 1936, Serial No. 99,071

13 Claims. (Cl. 200—116)

This invention relates to new and useful improvements in electrical circuit breakers.

One object of the invention is to provide an improved electrical circuit breaker which is particularly adapted for use in the usual fuse box, being substituted for the usual plug-type fuse.

An important object of the invention is to provide an improved electrical device arranged to be inserted in the usual electrical receptacle, and which will act as a thermostatic cutout or circuit breaker and which will not burn out or be destroyed when operated but may be restored to circuit closing position and repeatedly re-used.

Another object of the invention is to provide a plug-type circuit breaker which is arranged to produce a snap action in breaking the circuit and which requires manual resetting in order to again close the circuit; the structure being such that the circuit is broken during the re-setting operation, whereby danger of spark, as well as any danger of electrical shock to the operator is eliminated.

A further object of the invention is to provide an improved plug-type circuit breaker employing a resilient member sensitive to predetermined electrical variations and normally restrained to complete the electric circuit, but arranged to disengage itself and open said circuit upon predetermined circuit variations, there being means independent of the member for breaking the circuit while the member is being returned to its engaged position, whereby the circuit is not closed until the re-setting operation is complete.

A still further object of the invention is to provide an improved circuit breaker for use in an ordinary fuse box which is constructed of a minimum number of working parts and which has substantially the same size and shape as the usual plug-type fuse.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a circuit breaker, constructed in accordance with the invention,

Figure 2 is a transverse, vertical sectional view, showing the device in its circuit closing position,

Figure 3 is a similar view showing the same disengaged,

Figure 4 is an enlarged transverse sectional view with the housing omitted viewing the parts

from the side opposite to Figure 2, and showing the circuit closing position.

Figure 5 is a similar view, with the circuit broken,

Figure 6 is a similar view, showing the position of the part during the re-setting operation,

Figure 7 is an enlarged horizontal, cross-sectional view, taken on the line 7—7 of Figure 2,

Figure 8 is a transverse, vertical sectional view, taken on the line 8—8 of Figure 4,

Figure 9 is a transverse, vertical sectional view, taken on the line 9—9 of Figure 4,

Figure 10 is a transverse, vertical sectional view, taken on the line 10—10 of Figure 5,

Figure 11 is a transverse, vertical sectional view, taken on the line 11—11 of Figure 6,

Figure 12 is a transverse, vertical sectional view, taken on the line 12—12 of Figure 6,

Figure 13 is a horizontal cross-sectional view, taken on the line 13—13 of Figure 4,

Figure 14 is an isometric view of one side of the insulating block, and

Figure 15 is an isometric view of the other side of the block.

In the drawings, the numeral 10 designates a hollow, cylindrical shell or housing which is constructed of glass, or other electrical non-conducting material. One end of the housing is open while the opposite end is closed by an end wall 11, which wall is formed with an axial opening 12 therein. The end wall is preferably made integral with the housing or shell and an annular outwardly extending flange 13 is formed at this closed end of the shell. The shell or housing is substantially of the same size and shape as the ordinary plug-type fuse, whereby it may be inserted in the usual electrical receptacle which receives such fuse.

An insulating block 14, constructed of a suitable electrical non-conducting material is arranged to be inserted into the open end of the shell or housing 10. The block is substantially rectangular in cross-section, (Figure 13), having a length less than the diameter of the shell, and has a circular head or disk 15, constructed of the same material, integral with its outer end. The diameter of the head is substantially the same as that of the shell, and since the length of the block is less than the diameter of the shell, a peripheral flange 15' is formed around the block. When said block is inserted within the shell, the flange 15' engages the edge of the shell (Figures 2 and 3) and an annular metallic collar 16 which is threaded on the shell is provided with an inturned annular lip 17 which

engages the marginal portion of said head to fasten the head and block to the shell. The threads of the collar are formed by a pressing operation, whereby said collar is provided with 5 external, as well as internal threads. These external threads may be utilized for screwing the shell into the usual electrical receptacle which is provided for the reception of plug-type fuses. It is noted that the collar 16 may be riveted or otherwise 10 secured on the shell and the invention is not to be limited to threading said collar thereon, although this latter method makes for easy disassembling of the device.

For conducting electrical current through the 15 circuit breaker, the block 14 is provided with a laterally extending, narrow contact bar 18 at side thereof (Figures 4, 6 and 9), which bar is located near the upper end of the block. One end of the bar is disposed near the central portion of 20 the side of said block, while the opposite end is curved around one corner of the block so as to overlie the end thereof (Figure 13). A vertical bar 18' preferably a continuation of the bar 18 lies contiguous to this end of the block and has its 25 upper end integral with or otherwise connected with the contact bar. The bar 18' extends downwardly along the end wall of the block and passes through an opening 19 formed in the head or disk 15 (Figure 2). After passing through the 30 head, the bar is bent to lie contiguous to the head to form an elongate contact 20.

With this arrangement, it will be obvious that when the shell or housing is inserted into the usual electrical receptacle, the elongate contact 35 20 will engage the usual axial contact (not shown) which is provided in the receptacle, whereby electrical current flows through the bar 18' and to the contact bar 18. It is noted that the bar 18' and contact 20 need not be integral 40 with each other or with the contact 18, but it is preferable to make them so.

An L-shaped contact member 21 is set within the block 14 on the side opposite the bar 18 (Figures 2, 3, 9 and 10). The horizontal portion 21' of this member is located directly opposite the bar 18 and covers substantially one half of the side of said block. The laterally extending portion 22 of said member covers the lower portion of the other half of said block whereby the upper portion of the block above the portion 50 22 is exposed (Figures 2 and 3). The extreme upper end of the vertical portion 21' is formed with an outwardly curved lip 23 (Figures 9 and 12).

For electrically connecting the contact bar 18 on one side of the block with the contact member 21 on the opposite side, a metallic U-shaped connecting member or yoke 24 is positioned to span the block (Figures 2, 3 and 9). One of the 55 yoke arms is offset inwardly to provide an offset foot 25 which is adapted to engage the contact bar 18. The opposite yoke arm is formed with a latch 26, which is arranged to engage the lip 23 on the portion 21' of the member 21. The yoke is normally held in position with its arms 60 engaging the bar 18 and member 21 by a coiled spring 27 confined between the yoke and block (Figure 9). The spring surrounds a guide pin 28 which is slidable in a vertical opening 29 in the block, and this spring exerts its tension to 65 normally hold the yoke in a raised position with the latch 26 engaging the lip 23 and the offset foot 25 engaging the bar 18.

From the above, it will be seen that the electrical 70 current flowing through the bar 18 will

pass through the metallic yoke 24 and to the contact member 21. When the yoke is depressed or moved downwardly against tension of the coiled spring 27, it will be obvious that the offset foot 25 will ride off of the bar 18 and onto the exposed portion of the block therebeneath (Figure 12). Since the block is constructed of insulating material, this downward movement of the yoke will break the electrical circuit between the bar 18 and member 21. Of course, as soon as 10 the yoke is released, the spring 27 will immediately raise said yoke to re-engage the foot 25 with the bar 18 to again close the circuit.

A laterally extending contact plate 30 is mounted within the block 14 on the same side as is 15 the contact bar 18 (Figures 4, 5, 8 and 10). The plate is located directly opposite the laterally extending portion 22 of the member 21 and is disposed at the lower end of the block. It is noted 20 that there is no connection between this plate and the bar 18. The upper end of the plate is bent outwardly to form a lip or flange 31 which is located below an overhanging shoulder 32 provided on the block. The shoulder is formed by inclining the side of the block above the plate 25 outwardly at a slight angle from the vertical, as is clearly shown in Figures 8, 10 and 11.

The lower end of the plate is preferably made integral with a flat connecting bar 33 which overlies the flange 15' of the head. This bar 30 extends outwardly to the margin of the head and is then bent upwardly to provide a vertical contact bar 34. When the block is in position within the housing or shell, the contact bar 34 35 engages within a vertical recess 35 (Figure 7) provided in the outer surface of the shell, whereby the outer face of said bar is substantially flush with the surface of said shell. Thus, when the threaded collar 16 is in position on the shell, said collar engages the bar 34 to make electrical contact therewith.

For electrically connecting the plate 30 with the L-shaped contact member 21 on the opposite side of the block, a second U-shaped member or yoke 36 is provided. This yoke is constructed of 45 thermostatic or bi-metallic material, whereby it will undergo expansion or distortion under excessive heat. This metal of which the yoke is constructed of course, has an inherent resiliency or springiness and thus when said yoke spans the block 14, the arms of said yoke snugly engage the 50 opposite sides of the block (Figure 8).

One of the yoke arms 37 is adapted to engage the lateral portion 22 of the L-shaped contact member, while the opposite yoke arm 38 has its lower end bent inwardly to form a latch 39 for engaging the lip or flange 31 of the contact plate 30. A coiled spring 40 surrounds a guide pin 41 carried by the yoke and is confined between the yoke and block. The guide pin is slidable in a vertical opening 42 in the block, and the spring is, at all times, exerting its pressure to move the yoke upwardly. However, under normal conditions the yoke is depressed, as shown in Figure 8, with its arms closing the electrical circuit between the member 21 and plate 30. For depressing the yokes 24 and 36, a button 43 extends through the opening 12 in the end wall of the shell or housing. This button is constructed of insulating material and has an annular flange 44 at its lower end. The flange overlies both yokes and it is obvious that by depressing the button either one or both of the yokes may be depressed.

In operation, the housing or shell is inserted in

the usual electrical receptacle (not shown) and the yoke 24 is raised and engaging the contact bar 18 and member 21 (Figure 9) while the yoke 36 is depressed and engaging the member 21 and plate 30. With the yokes in this position, the electrical current will flow from the axial contact of the usual receptacle (not shown) to the elongate contact bar 20, through bar 18, yoke 24, member 21, yoke 36, plate 30, bar 34 and finally 10 to the metallic collar 16 and to the other side of the circuit in the receptacle to complete the electrical circuit. With the parts in this position, the circuit is closed as the current is flowing through both yokes 24 and 36 and their respective contacts. The bi-metallic yoke 36 is constructed so as to carry a predetermined flow of current and so long as normal conditions prevail, the parts remain in this position.

In the event that there occurs an overload or 20 short circuit in the current flowing through the device, the bi-metallic yoke 36 immediately becomes heated. This heating of said yoke causes an expansion of the same and such expansion disengages the latch 39 from the lip 31 of the 25 plate 30, permitting the coiled spring 40 to immediately raise the yoke. As the yoke moves upwardly, the arms thereof ride onto the exposed surface of the block and disengage the contact member 21 and plate 30, whereby the circuit between the contact bar 20 and contact bar 34 is broken. As said yoke moves upwardly, it raises the button 43 from the position shown in Figure 2 to that shown in Figure 3, to advise the observer that the circuit through the device is 35 broken. It is noted that upward movement of said yoke is limited by the engagement of the flange 44 with the inside of the end wall of the shell. Thus, as shown in Figure 10, the circuit is open since the current cannot flow through the 40 yoke 36 as said yoke has its ends engaging the insulating block.

As soon as the circuit is broken, the yoke 36 cools and the arms thereof immediately return to their normal position, snugly engaging the 45 sides of the block (Figure 10). It is pointed out that through the use of the latch 36 and lip 31, as well as the spring 40, a snap action in disengaging the yoke is obtained. This snap action is 50 advantageous as it reduces danger of arcing to a minimum. The yoke, after moving to its raised position will remain so until manually re-set.

When it is desired to re-set the yoke 36 to again close the circuit it is only necessary to depress the button 43. The flange 44 of this button engages the upper end of the yoke and moves the same downwardly under tension of the spring 40. It is noted that during the operation of the yoke 36, the yoke 24 has maintained its same raised position. Since the flange 44 of the button overlies both yokes, depression of said button in re-setting the yoke 36 will cause simultaneous depression of the yoke 24. Depression of this latter yoke will cause the offset foot 25 thereof, to ride off of the lateral contact bar 18, whereby electrical connection between this bar and the contact member 21 is broken. Therefore, so long as the yoke 24 is depressed no current can pass through this yoke.

The bar 18 is of such size and so positioned 70 with relation to the contact plate 30 that upon depression of both yokes 24 and 36, the yoke 24 breaks electrical connection between the bar 18 and member 21 before the yoke 36 is re-engaged with the plate 30 and member 21. In other words, 75 upon initial depression, the foot 25 rides off the

contact 18 before the latch 39 engages the lip 31 of the plate 30. Therefore, at the time the yoke 36 is re-set, no current is flowing through the device because the current is broken between the bar 18 and member 21. The circuit is therefore open during the resetting operation since one end of the yoke 24 is riding on the surface of the insulating block. Thus, all danger of arcing as the bi-metallic yoke approaches the plate 30 and member 21 is eliminated. This is an important 10 feature of the invention.

After the yoke 36 has been re-set, the button is released and the coiled spring 27 beneath the yoke 24 immediately raises said yoke to its original position (Figure 9) to re-engage the yoke arms with the bar 18 and member 21, whereby the circuit through the device is again complete. With this arrangement, it is obvious that the bi-metallic yoke 36 is re-set only when the circuit is broken and therefore, damage to said member because of arcing is obviated. Also 20 danger of any shock to the operator is eliminated because the electrical circuit through the device is not completed until the button is released.

What I claim and desire to secure by Letters 25 Patent, is:

1. A circuit breaker for engagement within an electrical receptacle including, an insulating block, electrical contacts mounted on said block, a bi-metallic element normally engaging the contacts to electrically connect the same, means for effecting a disengagement of said element from said contacts when said element is heated due to overload or short circuit, means for re-engaging said element, and means mounted on the block and connected in the circuit for breaking the electrical circuit to the contacts during the re-setting of said element.

2. A circuit breaker including, a shell adapted to be inserted into an ordinary electrical receptacle, an insulating block mounted within said shell, electrical contacts mounted on said block, a bi-metallic element normally engaging the contacts to electrically connect the same, means for effecting a disengagement of said element from said contacts when said element is heated due to overload or short circuit, means for re-engaging said element, and means mounted on the block and connected in the circuit for breaking the electrical circuit to the contacts during the 40 re-setting of said element.

3. A circuit breaker including, an insulating block, a pair of electrical contacts one on each side of said block, a bi-metallic yoke element spanning the block and having its arms engaging said contacts to electrically connect the same, means for normally holding said yoke arms in engagement with the contacts, means for effecting a disengagement of the yoke arms when said yoke becomes heated due to an overload or short circuit, means for re-setting the yoke after such disengagement, and means for cutting off the electrical current to the contacts during the re-setting operation.

4. A circuit breaker including, a shell adapted to be inserted into an ordinary electrical receptacle, an insulating block mounted within said shell, a pair of electrical contacts one on each side of said block, a bi-metallic yoke element spanning the block and having its arms engaging said contacts to electrically connect the same, means for normally holding said yoke arms in engagement with the contacts, means for effecting a disengagement of the yoke arms when said yoke becomes heated due to an overload or 60 65 70 75 80 85 90 95

short circuit, means for re-setting the yoke after such disengagement, and means for cutting off the electrical current to the contacts during the re-setting operation.

5. A circuit breaker including, an insulating block, electrical contacts mounted on said block, a bi-metallic element normally engaging the contacts to electrically connect the same, means for effecting a disengagement of said element from 10 said contacts when said element is heated due to overload or short circuit, means for re-engaging said element, means movable with relation to the block for breaking the electrical circuit to the contacts during the re-setting of said element, and manually operable means for simultaneously operating the last named means and the re-engaging means for said element.

6. A circuit breaker including, an insulating block, a pair of electrical contacts one on each side of said block, a bi-metallic yoke element spanning the block and having its arms engaging said contacts to electrically connect the same, means for normally holding said yoke arms in engagement with the contacts, means for effecting a disengagement of the yoke arms when said yoke becomes heated due to an overload or short circuit, means for re-setting the yoke after such disengagement, means for cutting off the electrical current to the contacts during the re-setting operation, and manually operable means for simultaneously operating the last named means and the re-engaging means for said element.

7. A circuit breaker including, a shell adapted to be inserted into an ordinary electrical receptacle, an insulating block mounted within said shell, electrical contacts mounted on said block, a bi-metallic element normally engaging the contacts to electrically connect the same, means for effecting a disengagement of said element from 40 said contacts when said element is heated due to overload or short circuit, means movable with relation to the block for re-engaging said element, means for breaking the electrical circuit to the contacts during the re-setting of said element, and manually operable means for simultaneously operating the last named means and the re-engaging means for said element.

8. A circuit breaker including, an insulating block, a contact bar mounted at one side of the 50 block and connected to one side of an electrical circuit, a contact member on the opposite side of said block, movable means for electrically connecting the bar and member, a contact plate on said block on the same side as the bar but having no electrical connection therewith, said plate being connected with the other side of the circuit, a movable bi-metallic element adapted to connect the plate with said contact member, means for effecting a disengagement of the element with the plate and member to break the circuit therebetween when the element is heated due to overload or short circuit, means for re-setting said element to again engage the plate 55 and member after disengagement, and means for moving the means connecting the contact bar and contact member to electrically disconnect the same during the re-setting whereby the electrical circuit is broken during the re-setting operation.

9. A circuit breaker including, an insulating block, a contact bar mounted at one side of the block and connected to one side of an electrical circuit, a contact member on the opposite 70 side of said block, movable means for electrically connecting the bar and member, a contact plate on said block on the same side as the bar but having no electrical connection therewith, said plate being connected with the other side of the circuit, a movable bi-metallic yoke 75

connecting the bar and member, a contact plate on said block on the same side as the bar but having no electrical connection therewith, said plate being connected with the other side of the circuit, a movable bi-metallic element normally 5 connecting the plate with said contact member, means for effecting a disengagement of the element with the plate and member to break the circuit therebetween when the element is heated due to overload or short circuit, and a single 10 manually operated means for re-engaging the element with the plate and contact member and for simultaneously moving the means connecting the contact bar and contact member to electrically disconnect said plate and member, whereby the electrical circuit is broken during 15 the re-setting.

10. A circuit breaker including, a shell adapted to be inserted within an ordinary electrical receptacle, an insulating block mounted within 20 said shell, a contact bar mounted at one side of the block and connected to one side of an electrical circuit, a contact member on the opposite side of said block, movable means for electrically connecting the bar and member, a 25 contact plate on said block on the same side as the bar but having no electrical connection therewith, said plate being connected with the other side of the circuit, a movable bi-metallic element normally connecting the plate with said 30 contact member, means for effecting a disengagement of the element with the plate and member to break the circuit therebetween when the element is heated due to overload or short circuit, means for re-setting said element to 35 again engage the plate and member after disengagement, and means for moving the means connecting the contact bar and contact member to electrically disconnect the same during the re-setting whereby the electrical circuit is broken 40 during the re-setting operation.

11. A circuit breaker including, a shell adapted to be inserted within an ordinary electrical receptacle, an insulating block mounted within 45 said shell, a contact bar mounted at one side of the block and connected to one side of an electrical circuit, a contact member on the opposite side of said block, movable means for electrically connecting the bar and member, a contact plate on said block on the same side as 50 the bar but having no electrical connection therewith, said plate being connected with the other side of the circuit, a movable bi-metallic element normally connecting the plate with said contact member, means for effecting a disengagement of the element with the plate and member to break the circuit therebetween when the element is heated due to overload or short circuit, and a single manually operated means 55 for re-engaging the element with the plate and contact member and for simultaneously moving the means connecting the contact bar and contact member to electrically disconnect said plate and member, whereby the electrical circuit is broken during the re-setting.

12. A circuit breaker including, an insulating block, a contact bar mounted at one side of the block and connected to one side of an electrical circuit, a contact member on the opposite side of said block, movable means for electrically connecting the bar and member, a contact plate on said block on the same side as the bar but having no electrical connection therewith, said plate being connected with the other side of the circuit, a movable bi-metallic yoke 70

- spanning the block and normally connecting the plate with said contact member, means for effecting a disengagement of the yoke with the plate and member to break the circuit therebetween when the yoke is heated due to overload or short circuit, means for re-setting said yoke to again engage the plate and member after disengagement, and means for moving the means connecting the contact bar and contact member to electrically disconnect the same during the re-setting whereby the electrical circuit is broken during the re-setting operation. 5
- 10 13. A circuit breaker including, an insulating block, a contact bar mounted at one side of the block and connected to one side of an electrical circuit, a contact member on the opposite side of said block, a yoke for electrically connecting the bar and member, a contact plate on said block on the same side as the bar but having no electrical connection therewith, said plate being connected with the other side of the circuit, a movable bi-metallic element normally connecting the plate with said contact member, means for effecting a disengagement of the element with the plate and member to break the circuit therebetween when the element is heated due to overload or short circuit, means for re-setting said element to again engage the plate and member after disengagement, and means for moving the yoke connecting the contact bar and contact member to electrically disconnect the same during the re-setting whereby the electrical circuit 10 15 is broken during the re-setting operation.
